TOY AIRPLANE

Henry J. Perker and Carl R. Anderson, Chicago,
Ill., assignors to Perand Products, Inc., Chicago,
Ill., a corporation of Illinois

Application June 15, 1949, Serial No. 99,146

1 Claim. (Cl. 46—61)

1

This invention relates to a new and improved toy airplane.

Simulation of flight for toy airplanes has long been sought. Motors have been used as well as other means to effect flight or at least partial flight of these toy planes. No one has successfully produced an economical toy airplane which would simulate actual flight.

It is therefore a principal object of this invention to provide an economically constructed toy airplane which is capable of moving through space in a manner corresponding to the flight of real airplanes.

An important object of this invention is the provision of means in a toy airplane for causing the plane to move downwardly and upwardly in a manner simulating the flight of airplanes.

Another important object of this invention is to supply rotatable inertia means journally carried in a toy airplane along with suitable string means for effecting an unwinding and thereafter a winding of the string means on the rotatable inertia means to create downward and upward "flight" of the toy airplane.

Another important object of this invention is to provide wheel means in a toy airplane constituting rotatable inertia means to provide the dual function of ground wheels and means to effect lowering and raising of the toy plane in the manner on a string means.

Another and still further important object of this invention is the provision of a toy airplane construction having a rotatable inertia member for effecting vertical "flight" of the plane and in cooperation therewith a restricted aperture in the body of the plane to guide movement of the inertia member operating strand.

A still further important object of this invention is to provide "threading" means for the operating strand of a rotatable inertia member into a restricted aperture in a toy airplane.

Another and further important object of this invention is the provision of a lever arm means in a toy airplane construction of the type having "flight" through a vertical path for maintaining the plane on an even keel.

Another and still further important object of this invention is to supply a toy airplane with a rotatable inertia member in the form of a plane propeller and conducive in the simulation of vertical flight of a plane.

A still further important object of this invention is to provide means in any size or shape of body member for effecting up and down movement of that member.

2

Other and further important objects and advantages will become apparent from the disclosures in the following specification and accompanying drawings:

- 5 In the drawings:
Figure 1 is a top plane view of a toy airplane of this invention.
Figure 2 is a front elevational view of the plane as shown in Figure 1.
10 Figure 3 is a side elevational view of the plane of Figures 1 and 2.
Figure 4 is a perspective view detail of a portion of the body of the plane of Figures 1, 2 and 3.
15 Figure 5 is a bottom plan view of a modified toy airplane.
Figure 6 is a side elevational view of the plane of Figure 5.
20 Figure 7 is a bottom plan view of a further modified form of toy airplane of this invention.
Figure 8 is a side elevational view of the plane of Figure 7.
As shown in the drawings:
25 The reference numeral 10 indicates generally a toy airplane having a longitudinally extending body 12 and laterally extending wing members 14 and 16. The wings are equipped with propellers 18 and 20 and each is mounted in a simulated engine mounting 22 and 24 respectively. The rearward portion of the body of the plane has short tail wings 26 and 28 as well as a vertically disposed rudder 30.

As best shown in Figure 2 the toy plane is provided with a large rotatable inertia member 32 comprising spaced side disc members 34 and 36 as well as a central annular slot 38. The member 32 doubles in function as a ground engaging wheel and device to effect simulated vertical "flight" of the toy plane by means of a string or strand 40 being wound or unwound in the annular slot 38 somewhat as a top.

As best shown in Figures 1, 2 and 3 the elongated body 12 substantially covers the rotatable inertia member 32 so that the outward appearance of the device is merely that of an airplane. The rotatable inertia member 32 is mounted for rotation on a shaft 42 carried in depending bracket members 46 from the wing members 14 and 16 respectively. The shaft 42 is located substantially on the center of gravity of the plane so that the plane is balanced from front to rear about this axis. The body 12 of the plane is equipped with a restricted aperture 48 in the top thereof and located above the rotatable inertia member 32. The string 40 is adapted to move

upwardly and downwardly through this aperture 48 for the purpose of effecting an up and down movement of the plane 10. It is of course the function of the rotatable inertia member to climb or roll up on the string 40 and by proper manipulation of the string by the operator the rotatable inertia member then rides down the string and vertical reciprocal movements can be continued by slight movements of the operator's hand while holding the upper end 50 of the string 40. The restricted aperture 48 performs several functions. Primarily it maintains the guiding of the string 40 and prevents wrapping of the string about anything but the hub of the annular slot 38. A second function attributable to the restricted aperture is its preventing swinging or rotatable movement of the entire plane 10 about the rotatable inertia member.

In executing the operation of this toy airplane the operator may, after a series of vertical movements, decide to permit the plane to come in contact with the ground and thereupon may release his grip on the upper end 50 of the string 40, and permit the wheel or rotatable inertia member 32 to continue its forward roll and thus carry the entire plane along the ground with the rotatable inertia member 32 acting as a ground wheel. It will be understood, of course, that as the rotatable inertia member rotates on the ground the string 40 will wind around in the annular slot 38 and pull the upper end 50 thereof through the restricted aperture 48 and continue rolling as long as the inertia of the wheel continues. Further or succeeding operations of the toy airplane will therefore necessitate the threading of the string upwardly through the restricted aperture 48. In order to facilitate this threading the following described special means is provided. As best shown in Figure 1 an enlarged aperture 52 is provided in the forward nose portion 54 of the body of the plane through which an operator may easily pass the end 50 of the string 40. A narrow slot 56 communicates with the restricted aperture 48 and the enlarged aperture 52 so that the string 40 may be pulled upwardly through the narrow slot till it reaches the restricted aperture 48. In order that the string remain in the aperture 48 during operation of the plane and particularly during flight operation thereof, a cross bar 58 is attached at 60 to the body portion 12 of the plane 10. The cross bar 58 lies over the narrow slot 56 and is positioned adjacent the restricted aperture 48. The bar 58 is relieved slightly on its underside as shown at 62 so that a string may be slipped under the bar and may enter the aperture 48 through the narrow slot 56 by a sidewise pulling of the string thereunder. Obviously during vertical reciprocation of the string 40 the string cannot leave the restricted aperture 48 and go downwardly through the slot 56 for the reason that the cross bar 58 lies in its path. Thus an effective string threading device is provided with the toy airplane of this invention.

Figures 5 and 6 show a modified form of toy airplane 64, also incorporating a rotatable inertia member 66 which consists of a pair of relatively widely spaced wheel members 68 and 70. Intermediate the wheels 68 and 70 is a spool-like member 72 for reception of a string 74. The wheel members and the spool are all rotatably mounted as a unit with a shaft 76 carried in depending brackets 78 and 80 from the plane wings 82 and 84 respectively. Similarly to the toy airplane 10 as shown in Figures 1 to 4 inclusive, the toy airplane 75

64 includes a body 86 having a nose 88, tail wings 90 and 92, and as shown in Figure 6 an upwardly extending rudder member 94. Figure 6 shows that the body 86 of the plane 64 also includes a restricted aperture 96 through which the string 74 may be confined for easy vertical reciprocal movements, but without transverse or lateral movements. It should be understood that threading means may be employed with the plane 10 of Figures 5 and 6 in the same manner as that employed for the plane of Figure 1. However, it was not deemed necessary to show the threading device associated with the plane of Figures 5 and 6. Operation of the toy airplanes 10 and 64 is substantially identical. The relatively widely spaced wheels 68 and 70 give the plane 64 more ground stability and prevent wing tipping of the plane 64.

Figures 7 and 8 show a further modified form 20 of airplane designated by the numeral 98. In the planes of 10 and 64 the rotatable inertia member was mounted on a transversely disposed axle or shaft, whereas in plane 98 the rotatable inertia member 109 is mounted on a longitudinally extending shaft 102. The shaft 102 is mounted in spaced bearings 104 and 106 in the forward and rearward ends of the body 108 of the airplane 98. The rotatable inertia member 109 in the present plane includes a simulated propeller member 110 and a spool 112 for receiving a string member 114. Operation of the plane 30 98 thus in addition to causing the plane to move in simulated vertical flight also causes rotation of the propeller 110 with respect to the body of the plane 108.

The body 108 of the plane 98 is provided with a restricted aperture 116 located directly above the string winding spool 112, thus guiding the movement of the string 114 onto the spool and permitting free and uninterrupted reciprocal movement. The plane 98 is provided with aligned laterally extending wing members 118 and 120. The plane 98 is further equipped with tail wings 122 and 124 and a rudder 126 similar in many respects to the appointments of planes 10 and 64. As best shown in Figure 7 wheel members 128 and 130 are provided beneath the wing members 118 and 120 by means of brackets 132 and 134 depending from the underside of these wings respectively. Each of the wheels 128 and 130 is mounted on a short shaft 136 and 138 respectively, journaled in the brackets 132 and 134. Primarily the wheels 128 and 130 are for ornamental purposes and simulate the ground wheels of a real airplane.

Vertical flight movement of the plane 98 differs quite a bit from the planes 10 and 64 because the rotatable inertia member is mounted for rotation on a longitudinal axis and the wings 118 and 120 tend to rotate with the propeller 110. In order to eliminate this tendency an inverted cone housing member 140 is attached to the body 108 at 142 and has an upwardly extending restricted aperture 144 at the top thereof, thus the restricted aperture 144 is spaced considerably above the first restricted aperture 116 and continues the functions of that first aperture and in addition provides through the cone member 140 a lever arm acting constantly to limit or prevent rotational movements of the entire plane about the shaft 102. There is no necessity for having a threading device associated with the plane of 98 for the reason that the ground engaging wheels do not rotate the rotatable inertia member to wind up the string 114 on the spool

112 as in the planes 10 and 64. However, the restricted aperture 116 along with the restricted aperture 144 performs the same function as the restricted aperture 48 and 96 of planes 10 and 64, respectively. Guiding of the string is an important factor in the successful operation of the toy airplane of this invention.

Although the specification mentions toy airplanes as the embodiment of the rotatable inertia member it is obvious that it could be built into the housing of any device or toy to effect vertical reciprocal movement. Such toys include dirigibles, blimps, balls, automobiles, or any device having a housing within which a rotatable inertia member may be journaled.

Numerous details of construction may be varied throughout a wide range without departing from the principles disclosed herein, and we therefore do not propose limiting the patent granted hereon otherwise than as necessitated by the appended claim.

What is claimed is:

A toy comprising a body structure, rotatable inertia means journally carried by said body structure, shield means forming part of said body structure and covering at least the top portion of said rotatable inertia means, said shield means

provided with a restricted opening in the top thereof, string means attached to said rotatable inertia means and extending upwardly through said restricted opening, whereby the toy may be moved downwardly and upwardly by manipulation of the string means, means for threading the string from the rotatable inertia means through the restricted opening, and said means for threading including the body structure having a slot extending from a position adjacent the rotatable inertia means to the restricted opening and a finger attached at one end to said body structure and having a free end extending across said slot adjacent the restricted opening, whereby the string may be passed through said slot and under said finger to enter the restricted opening.
